DISPLAY AND DISPENSING UNIT

Alfred L. Snape, Stoughton, Mass., assignor to The Gillette Company, Boston, Mass., a corporation of Delaware

Filed Apr. 4, 1961, Ser. No. 100,530

5 Claims. (Cl. 206—78)

This invention comprises a new and improved device or unit useful in packing, displaying and dispensing for prospective customers small articles of commerce, such for example as razor blades or packages thereof.

The invention is herein disclosed in its application to the sale of magazines or dispensers containing a selected number of safety razor blades. The embodiment of the invention disclosed herein includes in its structure a display card and an attached attractive transparent enclosure for containing an article of commerce in full view to provide a unit that can withstand considerable rough handling and yet can easily be opened to remove the article. The unit is well organized to be manufactured with a high degree of accuracy from easily produced parts.

An important feature of the invention consists in providing the display card with a transverse scored fold line and attaching a stiff transparent enclosure in a position to overlap or cross the fold line. The top edge of the enclosure may then readily be separated from the card by folding the card along the scored line to facilitate further separation of the enclosure and card to expose the contained article. The enclosure is preferably molded of a synthetic resin that provides stiff marginal flanges that supply plane flat areas for the adhesive and facilitate separation of the card from the enclosure when the card is folded or bent away from them.

These and other features of the invention will be best understood and appreciated from the following description of preferred embodiments thereof, selected for purposes of illustration and shown in the accompanying drawings, in which:

FIG. 1 is a view of the unit in front elevation.

FIG. 2 is a corresponding sectional view on the line 2—2 of FIG. 1, showing in dotted lines the position of the folded portion of the card,

FIG. 3 is a view in rear elevation, and

FIG. 4 is a view similar to FIG. 1 of a second embodiment of the invention.

The unit in the form illustrated herein includes a rectangular display card 10 of cardboard or other stiff sheet material. The upper portion of the card may be devoted to advertising or announcement of price and is herein shown as having perforations 11 by which the unit may be hung in conspicuous position if desired. The card 10 is divided by a deeply scored transverse fold line 12 that extends from edge to edge.

A removal area is set off in the lower half of the card by the scored line 12 together with spaced parallel slits 13 extending downwardly from the fold line nearly to the lower edge of the card.

A rectangular enclosure or blister 14 is molded of transparent sheet material, such as polystyrene or methylmethacrylate with a stiff marginal flange 15 which merges into an outwardly offset body shaped to contain a blade magazine 16 or other article to be displayed for sale. The body of the enclosure is of sufficient rigidity to maintain permanently its molded shape and to afford adequate protection to its contents. The bottom and side portions of the flange 15, FIG. 4, of the enclosure 14 are adhesively secured to the lower portion of the face of the card 10 with the enclosure in such position that its top flange portion overlaps or crosses the scored fold line 12

2

and preferably with its lower flange reinforcing the lower edge of the card. This confines the magazine 16 within the enclosure in front of the area of the card defined by the slits 13 and the scored fold line 12. The top flange of the enclosure 14 may if desired be adhesively secured to the card at a limited area 20, FIG. 1, substantially halfway between the sides of the enclosure in which case a slit 18 is made in the card therebeneath. The slit 18 may suitably be made in the scoreline 12.

Now, when it is desired to separate the enclosure 14 with its magazine 16 from the card it is only necessary to fold or bend the card rearwardly on the fold line 12 as suggested in dotted lines in FIG. 3. This will cause the card to tear away from the stiff flanges 15 of the enclosure. The magazine, which has been fully protected up to this point, may now be fully exposed for removal by gripping the freed end of the enclosure and tearing it away from the card. The flange 15 will carry with it the top surface of the card where it is adhesively secured thereto but the peeled-off surface portions will be confined to areas of the card outside of the removal area between the slits 13 and below the cut 18 leaving the latter area free and unobstructed.

It will be apparent that the slits 13 may be spaced apart so that the opening formed in the card will permit the magazine to drop out when the enclosure is tilted or they may be spaced to leave retaining edges of the card surface for temporarily holding the magazine within the enclosure 14 to prevent it from accidentally dropping out but to permit ready removal thereof.

The enclosure 14 is provided with a peripheral shoulder 22 that permits preformed enclosures to be nested together in a stack with uniform spacing between the flanges 15. This facilitates packing and shipping of preformed enclosures and also permits them to be picked up individually, loaded and assembled to cards by automatic packaging apparatus.

The magazine is of itself an article of attractive design and its appearance is enhanced by framing within the transparent enclosure. As a result the assembled unit is of sufficiently pleasing appearance to attract the favorable notice of the customer.

Having thus disclosed my invention and described in detail an illustrative embodiment thereof, I claim as new and desire to secure by Letters Patent:

1. A device for dispensing and displaying an article of commerce comprising a display card having an intermediate fold line scored across it and parallel slits defining a removal area of said card and a transparent enclosure of plastic material having a stiff flange adhesively secured directly to said card, said flange having top and bottom sides, one of said sides being positioned above said scored line and having its inner portion positioned in approximately the same plane as said fold line, said flange also including side portions adhesively secured to said card on both sides of said line, said flange merging into a rectangular body enclosing an article upon the said removal area of said card whereby separation of said enclosure with its contents along said slits is facilitated by folding said card at said scored line.

2. A device for dispensing and displaying an article of commerce comprising a display card having a fold line scored therein and a transparent enclosure including a body portion shaped to contain the article and a stiff, flat marginal flange adhesively secured directly to the face of said card, said flange having top and bottom sides, one of said sides being positioned above said fold line and having its inner portion positioned in approximately the same plane as said fold line, said flange also including side portions adhesively secured to said card on both sides of said line whereby the card may be forcibly sepa-

rated from said flange by folding said card on said scored fold line.

3. A device for dispensing and displaying articles of commerce comprising a display card having a transverse scored line therein, in combination with an enclosure of transparent plastic material having a flat, stiff marginal flange adhesively secured directly to said card, said flange having top and bottom sides, the top side being positioned above said fold line and having its inner portion positioned in approximately the same plane as said scored line, said flange also including side portions overlying and adhesively secured to said card on both sides of said scored line, and the bottom flange side reinforcing the lower edge portion of said display card, said flange merging into a body portion shaped to correspond to the article to be dispensed.

4. A device for dispensing and displaying rectangular articles of commerce comprising a display card having an intermediate fold line scored across it, an enclosure of transparent material having a flat, stiff marginal flange 20 having four sides, three of said sides only being adhesively secured directly to said card, said card being provided with a pair of spaced slits normal to the fourth side and within the confines of said enclosure, said fourth side being positioned above said fold line and having its inner portion positioned in approximately the same plane as said fold line, and two of said three sides having portions thereof adhesively secured to said card above and below said fold line.

5. A device for dispensing and displaying articles of commerce comprising a display card having a transverse scored line therein, in combination with an enclosure of transparent plastic material having a flat, stiff marginal flange adhesively secured directly to said card along the side and bottom flange portions and at a limited area on the top flange portion intermediate the ends thereof, said top flange portion positioned above said scored line and having its inner portion positioned in approximately the same plane as said scored line, said card having a slit immediately below said limited area along said score line and a pair of spaced slits within and parallel to said side flange portions, thereby providing a removal area free of obstructing card portions adherent to said flanges upon separating said card and enclosure.
